(57) **CLAIM**

The ornamental design for a wireless microphone set, as shown and described.

DESCRIPTION

FIG. 1 is a front, top perspective view of a wireless microphone set, showing my new design;

FIG. 2 is a rear, bottom perspective view thereof;

FIG. 3 is an exploded view of FIG. 1;

FIG. 4 is a front, top perspective view of a first piece of the wireless microphone set;

FIG. 5 is a rear, bottom perspective view thereof;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a top plan view thereof;

FIG. 11 is a bottom plan view thereof;

FIG. 12 is a front, top perspective view of a second piece of the wireless microphone set;

FIG. 13 is a rear, bottom perspective view thereof;

FIG. 14 is a front elevation view thereof;

FIG. 15 is a rear elevation view thereof;

FIG. 16 is a left side elevation view thereof;

FIG. 17 is a right side elevation view thereof;

FIG. 18 is a top plan view thereof;

FIG. 19 is a bottom plan view thereof;

FIG. 20 is an enlarged view of detail "20" identified in FIG. 12;

FIG. 21 is a front, top perspective view of a third piece of the wireless microphone set;

FIG. 22 is a rear, bottom perspective view thereof;

FIG. 23 is a front elevation view thereof;

FIG. 24 is a rear elevation view thereof;

FIG. 25 is a left side elevation view thereof;

FIG. 26 is a right side elevation view thereof;

FIG. 27 is a top plan view thereof; and,

FIG. 28 is a bottom plan view thereof.

The dashed lines in the figures illustrate portions of the wireless microphone set that form no part of the claimed design. The dash dot dash broken lines in FIGS. 12 and 20 are for the purpose of illustrating the enlarged view indicators and form no part of the claimed design.
